His Attorneys.

UNITED STATES PATENT OFFICE.

HENRY HAVER, OF ST. LOUIS, MISSOURI.

SIGNAL.

Application filed March 14, 1921. Serial No. 452,155.

To all whom it may concern:

Be it known that I, HENRY HAVER, a citizen of Austria, and a resident of St. Louis, Missouri, have invented a new and useful 5 Signal, of which the following is a specification.

This invention relates to signals.

An object of the invention is to provide a 10 novel and efficient signal for use in connection with vehicles to indicate to vehicles approaching from the rear or from the front that the vehicle bearing the signal is about to stop or to change its direction.

Another object of the invention is to provide 15 an improved signal of the character mentioned having illuminating means whereby the signal is made visible at night.

Other objects of the invention will appear 20 from the following description, reference being made to the drawing in which—

Fig. 1 shows the invention applied to an automobile.

Fig. 2 is an elevation of my improved 25 signal detached from an automobile.

Fig. 3 is an inner end elevation.

Fig. 4 is a longitudinal sectional view.

Fig. 5 is a cross sectional view.

Fig. 6 is a detailed sectional view showing 30 details of the invention.

In the particular embodiment shown my 35 invention is of a type adapted to be applied to the windshield support or to any other appropriate location in which the signal can be properly controlled.

As shown, the signal and the controlling 40 means therefor are mounted in a bracket comprising a tubular portion 1 and bracket arms 2. In the construction shown the bracket arms 2 are provided with cooperating clamp members 3. The windshield support 4 is claimed between the arms 2 and the clamping members 3. The clamping devices for setting the clamps comprise screws 5 mounted in threaded holes in the 45 clamping members 3 and having their ends bearing against the arms 2; and screw bolts 6 passing through threaded holes in the arms 2 and also through threaded holes through the clamping members 3 and constituting 50 means for setting the clamps.

The tubular portion 1 of the bracket supports a case comprising a cylindrical member 7 and an inner end wall 8. The hub of the end wall 8 is secured to a sleeve 9 enclosing the tubular part 1 of the bracket. 55

The case is held rigidly in proper adjustment on the bracket by screws 10 passing through the hub of the end wall 8 and engaging in threaded holes in the tubular arm 1 of the bracket. Holes for the reception of screws 10 are formed at different intervals along the bracket arm so that the length of the signal device may be varied by securing the case at selected distances from the end of the bracket arm. 60 The outer end of the case comprises a frame 11 and an appropriately colored and shaped glass panel 12 which, when the vehicle is stationary, may be made to serve as a parking signal or lamp, and may also take the 65 place of a tail light when the vehicle is in use.

The forward and rear sides of the case 7 are cut out to form openings, and the openings so formed are covered by windows 13. 75

A hollow rod 14 is mounted for rotation in the part 1 of the bracket. The rod 14 extends into the case 7 and supports a cylinder 15 upon which are arranged appropriate signals that may be brought opposite the 80 windows 13 by turning the signal device properly. As the windows 13 are diametrically opposite the preferred arrangement is to provide similar signals and arrange them diametrically opposite each other on the 85 cylinder 15, so that like signals will be shown through the forward and rear windows 13 at the same time. For instance, as shown in Fig. 2, the signal "Stop" is opposite the rear window 13, and it will be understood 90 that the same signal is shown opposite the front window 13 during the time that this signal is at the rear window. It is intended that other signals indicating change of direction or that the vehicle is proceeding 95 straight ahead, or to give other desired notice to approaching vehicles, are also on the cylinder 15 and may be placed opposite the front and rear windows by proper operation of the device.

An electric lamp 16 is supported by the inner end of the rod 14 and a wire 17 in circuit with the lamp leads to a binding post 18. The binding post 18 is supported by a spring 19 attached to a lever 20 that is secured to the inner end of the rod 14. The binding post 18 is insulated from the lever 20 and extends through a hole in said lever and is arranged to be brought into contact with various contact members 21 on a sup- 105 110

port 22 carried by the bracket. A circuit wire 23 is connected with the support 22, so that when the contact member 18 is brought into contact with any one of the contact members 21 the circuit is completed and the lamp 16 is lighted. However, when the contact member 18 is out of contact with the contact members 21 the circuit to the lamp is open and the lamp is not lighted.

10 The member 22 has an arcuate edge provided with a number of notches 24 adapted to receive a detent 25 movably mounted in the lever 20 and actuated toward the support 22 by a spring 26. Since the detent 25 is spring-pressed into the notches 24 it is apparent that the lever 20 will be latched and held from movement by such engagement of the detent 25 in said notches. Since the walls of the notches are inclined the lever may be manually moved in either direction. The notches 24 are arranged relative to the contact members 21 so that the circuit to the lamp is closed in any position of the lever in which said latching engagement occurs.

15 The arrangement is such that when the lever 20 is in the position shown two identical signals are displayed opposite the windows 13. By raising the lever 20 to the next latched position different identical signals will be displayed opposite the windows; and by moving the lever to still a different latched position other identical signals will be displayed opposite the windows 13, and so on.

20 From the foregoing it will be seen that my invention completely serves all of its intended purposes and that by use of the device all useful and necessary signals may be given. The fact that the signal is illuminated automatically and as an incident to its operation is a useful feature, and the further fact that the signal may be used as a parking signal is also an advantage.

25 I do not restrict myself to unessential features, but what I claim and desire to secure by Letters Patent, is:—

1. A signal of the character described,

comprising a rigid horizontal arm, a case rigidly supported by the arm and having its outer end at right angles to its forward and rear sides, a semispherical, outwardly projecting window closing the outer end of the case, and being visible from the front and rear and serving as a parking light, windows in the forward and rear sides of the case, a cylinder rotatively mounted in the case and having its outer end adjacent to the first-named window open, signals on the periphery of said cylinder, a lamp within the cylinder for illuminating the first-named window whenever the lamp is lighted and for illuminating said signals whenever said signals are opposite said forward and rear windows, a lever for turning the signals to and from different adjusted positions to place different signals opposite said windows or out of line with said windows, and an electric circuit controlled by said lever for illuminating said lamp.

2. A signal of the character described, comprising a rigid horizontal arm, a case supported by said arm, means for holding said case rigidly in different desired positions along the length of the arm, a semispherical, outwardly projecting window closing the end of said case opposite the outer end of said arm, and being visible from the front and rear and serving as a parking light, a cylinder rotatively mounted within the case and having an open end adjacent to said window, signals on the periphery of said cylinder, windows in the forward and rear sides of said case, a lamp within said cylinder between said forward and rear windows and in line with said first-named window, a lever for turning said cylinder to and from different positions to place different signals in or out of line with said forward and rear windows as desired, a device for turning said cylinder to place the signals as aforesaid, and an electric circuit controlled by said device for illuminating said lamp only when the signals are opposite said forward and rear windows.

HENRY HAVER.
